Primary Examiner — April Rivas(74) *Attorney, Agent, or Firm* — Kirk A. Buhler; Buhler & Associates(57) **CLAIM**

The ornamental design for a collapsible foldable storage bag, as shown and described.

DESCRIPTION

FIG. 1 is a top perspective view of a collapsible foldable storage bag, showing our new design;

FIG. 2 is a front elevation view thereof;

FIG. 3 is a rear elevation view thereof;

FIG. 4 is a left side elevation view, the right-side elevation view being a mirror image thereof;

FIG. 5 is a right-side elevation view with the lower flap open, the left side elevation view with the lower flap open being a mirror image thereof;

FIG. 6 is a top plan view thereof; and,

FIG. 7 is a bottom view thereof.

The broken lines in FIGS. 4 and 5 depict environmental subject and form no part of the claimed design.

The even-length broken lines within the figures represent stitching and form no part of the claimed design.

1 Claim, 5 Drawing Sheets(56)
